OF NAPA, CALIFORNIA.

BENCH VISE.

1,417,025.

Specification of Letters Patent. Patented May 23, 1922.

Application filed October 20, 1921. Serial No. 508,976.

To all whom it may concern:

Be it known that I, WILLIAM H. BRYAN, Jr., a citizen of the United States, residing at Fresno, in the county of Fresno and 5 State of California, have invented new and useful Improvements in Bench Vises, of which the following is a specification.

This invention relates to bench vises, and especially to a foot operated type of vise of 10 the character disclosed in United States Letters Patent No. 969,003, issued to Elmer E. Thayer August 30th, 1910.

In the type of vise under consideration the movable jaw is carried on a ratchet 15 toothed bar slidably mounted in a stationary frame. Normally the sliding bar is free to be moved by hand to the desired position of adjustment and then by means of a foot operated bell crank lever and connected toggle 20 mechanism a slideable pawl is brought into engagement with the ratchet teeth on the bar to force the movable jaw into clamping position. Locking mechanism for the bell crank lever is also provided and this is so 25 arranged as to be released by a slight pressure of the foot. Aside from being much faster than the screw feed vises the foot control leaves both hands of the operator free for other duties.

30 The present invention has for its object to improve and simplify the operation and construction of bench vises of the character above mentioned. Chief among the particular improvements embodied in the present invention is the provision of novel means to obtain a finer adjustment in the operation of the jaw actuating mechanism, and likewise the provision of means to render the vise adjustable as to height.

40 In the accompanying drawings:

Fig. 1 shows a side elevation of a bench vise embodying my invention.

Fig. 2 shows an end elevation of the same.

Fig. 3 shows a detailed sectional view 45 of the locking mechanism for the bell crank actuating member.

Fig. 4 shows a detailed sectional view of the slideable pawl for actuating the rack which carries the movable jaw.

50 By way of example I have illustrated a carpenters' bench vise, although the same mechanism is capable of use in mechanics' bench vises. A conventional form of bench is indicated at 10. The frame of the vise 55 comprises an upright tubular post 11 fitted

at its lower end with a pedestal or base 12 resting on the floor. Telescopically mounted within the tubular member is a shank 13, which carries a stationary jaw 14 and a guide frame 15. Slidably mounted within 60 the guide frame is a bar 16 formed with ratchet teeth 17 on its under side, and carrying a clamping jaw 18 at its outer end.

As shown in detail in Fig. 4, the guide frame 15 has its side walls extending below 65 the bar 16 and receiving between them a pawl 19 supported pivotally by means of a transverse pin 20, the latter being fitted in horizontal slots 21 formed in the extension side walls of the guide member. This pawl has 70 a plurality of serrations or teeth 22 to insure instant engagement with the ratchet teeth on the bar 16. The heel 23 of the pawl is weighted so that the teeth at the opposite end will engage the ratchet teeth 75 on the bar. Fixed upon the guide frame in position to cooperate with the heel portion 23 when the pawl is in its outermost or retracted position is a cam or inclined lug 24, the action of which is to lift the heel portion 23, causing the teeth 22 of the pawl to 80 disengage the ratchet teeth on the bar 16.

Connected also to the pin 20 is a toggle link 25. A companion toggle link 26 is connected to the guide frame 15 at the opposite 85 end and the two links are pivotally connected to each other and to an operating rod 27. This operating rod has a long screw-threaded connection with a block 29 pivotally mounted in the end of a short arm 30 of a 90 bellcrank lever 31. The angle or axis of the bell crank lever is supported pivotally in a bearing 32 fixed upon the tubular post 11, and the long arm of the bell crank lever extends downwardly behind the post and is 95 formed at its lower end with an angular pedal portion 33 which extends through an opening in the base member 12.

The pedal extension is provided with a toothed rack 34 on its under side, and cooperating therewith is a novel locking mechanism, the details of which are shown 100 in Fig. 3. Pivotally mounted on the base member 12 and extending through the opening therein is an arm 35 which carries a pinion 36 in position to engage the teeth on the rack 34. Locking dogs 37 mounted upon the swinging arm 35 are arranged at opposite sides of the pinion 36 and are held 105 by means of springs in contact with the 110

bar, toggle links for actuating said pawl, a bell crank lever for spreading said toggle links apart, a pedal extension on said bell crank lever, and locking mechanism for said bell crank lever, comprising a toothed rack on the pedal extension, a pinion to engage the rack, a plurality of locking dogs for said pinion, engageable alternately with the teeth thereof, a pivotally mounted member carrying said pinion and dogs, a spring for retaining said pivotally mounted member in position where the pinion will engage the teeth of the rack, and means adjacent the pedal extension for permitting the pivotally mounted member to be depressed whereby to

disengage the pinion from the toothed rack.

5. In a bench vise of the foot operated type, a slideable toothed bar carrying one of the jaws, a sliding pawl for operating said bar, toggle links for actuating said pawl, a bell crank lever for spreading the toggle links apart to operate the pawl, and a thrust rod pivotally connected with the toggle links and having a screw-threaded connection with the bell crank lever, for operating said toggle links whereby the distance between the toggle links and bell crank lever may be varied.

WILLIAM H. BRYAN, JR.
